(57) **CLAIM**

The ornamental design for a pouff seat as shown and described.

DESCRIPTION

1. Pouff seat

1.1 : Front

1.2 : Back

1.3 : Left

1.4 : Right

1.5 : Top

1.6 : Bottom

1.7 : Fully assembled perspective

1.8 : Partially exploded perspective

1.9 : Fully exploded perspective

Modular pouff seat; the thin irregular lines on the surfaces of the claimed design show shading that defines the contours of the modular pouff seat and do not reflect a particular surface ornamentation or material.
